UNITED STATES PATENT OFFICE.

JOHN S. WALKER AND SYLVESTER N. WILCOX, OF PITTSBURG, PENNSYLVANIA.

HEATER.

No. 918,935.

Specification of Letters Patent.

Patented April 20, 1909.

Application filed January 23, 1908. Serial No. 412,282.

To all whom it may concern:

Be it known that we, JOHN S. WALKER and SYLVESTER N. WILCOX, citizens of the United States of America, residing at Pittsburg, in the county of Allegheny and State of Pennsylvania, have invented certain new and useful Improvements in Heaters, of which the following is a specification, reference being had therein to the accompanying drawing.

10 This invention relates to heaters, and relates more particularly to that class of heaters wherein gas is used as a heating medium for heating air within the heater, prior to the discharge of the air from the heater and 15 its distribution to the compartments of a building.

The primary object of our invention is to provide a novel heater having a large area of heating surface to which the cold air admitted to the heater is subjected, in order 20 that the air will be thoroughly heated before being discharged from the heater.

A still further object of our invention is to provide a heater wherein a circuitous or 25 sinuous path is provided for the products of combustion whereby a high degree of efficiency can be obtained from a minimum expenditure of fuel.

With the above and other objects in view 30 which will appear as the invention is more fully described, the same consists of the novel construction, combination and arrangement of parts to be hereinafter more particularly described and then specifically claimed.

35 In describing the invention in detail, reference will be had to the accompanying drawings forming a part of this application, and wherein like numerals of reference will be employed to indicate like parts throughout 40 the different views of the drawings, in which:

Figure 1 is a central vertical sectional view of a heater constructed in accordance with our invention. Fig. 2 is a horizontal sectional view taken on the line 2—2 of Fig. 1. 45 Fig. 3 is a similar view taken on the line X—X of Fig. 1, and, Fig. 4 is also a horizontal sectional view taken on the line Y—Y of Fig. 1.

To put our invention into practice we provide 50 an outer shell or casing 1 which, in practice, is usually supported upon legs 2, and is generally provided with a frusto-conical top 3 having a plurality of exit flues 4.

Secured to the inner face of the outer shell 55 or casing 1, some distance above the lower

end thereof, is a plurality of substantially U-shaped supporting brackets 5^a. One leg of each of these brackets is secured to the outer casing or shell 1, and to the other leg of each bracket is secured the inner casing or shell 5, 60 the brackets serving not only as a support for the inner shell, but as a means for spacing the inner shell away from the outer shell or casing 1. The said inner shell 5 is provided with depending legs 6 which rest upon and 65 are secured as by riveting to a casing 6^a which practically constitutes the combustion chamber 6^b, the said casing 6^a extending to the top of the inner casing 5, and having a closed upper end as clearly seen in Fig. 1. 70 The legs 6 being attached to the casing 6^a near the lower end of the latter help to support this casing, and also act as a support for a double-wall drum to be hereinafter further described.

75 The casing 6^a forming the wall of the combustion chamber 6^b is provided with a doorway casing 7, normally closed by a suitable door 8. Extending into the combustion chamber, preferably through the bottom of 80 the casing 6^a is a gas supply pipe 9 which supplies gas to a burner 10 of any desired form and located in the combustion chamber, and in connection with which it is preferable to use porcelain heat retaining members 11 as 85 shown.

Mounted in the casing 5 and resting on the shoulders 12 of the legs 6, is a double wall drum 13, the outer wall of said drum snugly fitting the casing 5, and the upper end of the 90 drum being closed by an annular plate 14, riveted around its outer edge to the flanged upper end of the outer wall of the drum as at 15, said flanged upper end of the outer wall of the drum resting upon the upper end 95 of the casing 5. The inner wall of the drum 13 is also flanged at its upper end as shown at 20^a, the said flange extending in the opposite direction to the flange on the upper end of the outer wall of said drum. The inner 100 edge of the annular plate 14 comes flush with the inner edge of said flange 20^a, so as to leave an annular opening 20^b through which the heated air escapes into the chamber in the upper part of the casing or shell 1, from where it is discharged through the exit flues 4 into the compartments of a building in the usual manner. The annular plate 14, in addition to the securing means 105 15, is firmly held in place by means of a 110

spider 14^a riveted at 14^b to the closed upper end of the casing 6^a and the arms of which are held by the rivets 15.

In the space between the outer and inner walls of the drum 13 is arranged a spiral partition 16 providing a circuitous or sinuous passage-way 17 winding from the bottom of the space between the inner and outer walls of the drum to the top thereof. The said 10 space between the inner and outer walls of the drum 13, communicates at the bottom of the drum, as by a pipe 18, with the combustion chamber within the casing 6^a, and in front of the inner end of the pipe 18, is 15 provided the shell 6^a with a vertical flue 19 extending in close proximity to the closed upper end of said shell 6^a.

The products of combustion after being carried through the circuitous path between 20 the inner and outer walls of the drum, are led off through an exhaust flue 20, adapted for connection with a stack or chimney (not shown).

In operation, the gas is ignited at the 25 burner, access being had to the burner through the door-way 7. The products of combustion pass upwardly in the shell 6^a, their outlet from this shell being downwardly through flue 19, and through pipe 18 into 30 the space between the inner and outer walls of the drum 13. Owing to the spiral partition arranged between the walls of the drum, the products of combustion are caused to pass upwardly between these walls in a circuitous manner, and are thereby retained 35 in the chamber a sufficient length of time to cause the walls of the drum, and also the inner casing 5 to become thoroughly heated, before the products of combustion are 40 finally discharged from the top of the drum chamber through the exhaust flue 20. The air to be heated in the heater, and after being heated distributed to the various compartments of a building, passes into the bottom 45 of the outer casing or shell 1 and upwardly between the inner shell 6^a and the inner wall of the drum 13, and escapes through the annular opening 14 into the chamber at the upper end of the shell or casing 1 from 50 whence it passes to the building through the exit flues 4. Cold air also passes upwardly

between the outer casing or shell 1 and the inner casing 5, and during its upward passage is thoroughly heated by the heat given off by the casing 5. During the passage of 55 cold air upwardly between the outer casing or shell 1 and the casing 5 and also between the inner wall of the drum and the casing 6^a, the air is thoroughly heated by the heat given off by the walls of the drum and casing 60 5, before being discharged into the chamber at the top of the casing 1 and from thence delivered to the building.

Having fully described our invention what 65 we claim is:

A heater comprising an outer shell or casing, an inner casing mounted in said outer shell or casing and spaced therefrom, brackets secured to said outer shell or casing and supporting said inner shell or casing, a double wall drum mounted in said inner casing with its outer wall fitting the inner casing and having a flange at the upper end of said outer wall overlying the top of said inner casing, legs carried by said inner casing for 70 supporting said drum, a spiral partition arranged in the space between the walls of said drum, a combustion chamber casing having the upper portion thereof surrounded by said drum and provided with a closed upper 75 end, a vertical flue within said combustion chamber casing, a pipe establishing communication between said flue and the space between the walls of the drum at the lower end of the latter, an exhaust pipe communicating with the space between the walls of the drum at the upper end of the latter, an annular plate secured to the flanged upper 80 end of the outer wall of said drum, and a spider secured to the closed upper end of the 85 combustion chamber casing and having its arms secured to said annular plate and the flanged upper end of the outer wall of said drum.

In testimony whereof we affix our signatures in the presence of two witnesses.

JOHN S. WALKER.
SYLVESTER N. WILCOX.
